UNITED STATES PATENT OFFICE

157,768

REFRIGERATOR CABINET

John M. Little, Toledo, Ohio, assignor to Westinghouse Electric Corporation, a corporation of Pennsylvania

Application November 5, 1948, Serial No. 149,488

Term of patent 14 years

(Cl. D67—3)

To all whom it may concern:

Be it known that I, John M. Little, a citizen of the United States, residing at Toledo, in the county of Lucas and State of Ohio, have invented a new, original, and ornamental Design for a Refrigerator Cabinet, of which the following is a specification, reference being had to the accompanying drawing, forming a part thereof.

Fig. 1 of the drawing is a perspective view of a refrigerator cabinet embodying my new design;

Fig. 2 is a side elevational view of the refrigerator cabinet;

Fig. 3 is a sectional view of a front element of the refrigerator cabinet taken on the line III—III of Fig. 1; and

Fig. 4 is a sectional view of another front element of the refrigerator cabinet taken on the line IV—IV of Fig. 1.

The side of the refrigerator cabinet not shown

in the drawings is substantially like the side shown therein.

I claim:

The ornamental design for a refrigerator cabinet, substantially as shown and described.

JOHN M. LITTLE.
